UNITED STATES PATENT OFFICE.

GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

PULL-SOCKET.

1,246,493.

Specification of Letters Patent.

Patented Nov. 13, 1917.

Application filed December 18, 1915. Serial No. 67,618.

To all whom it may concern:

Be it known that I, GEORGE B. THOMAS, a citizen of the United States of America, and residing at Bridgeport, in the county of 5 Fairfield and State of Connecticut, have invented a certain new and Improved Pull-Socket, of which the following is a specification.

My invention relates to pull sockets and 10 particularly to a novel construction and arrangement of the socket parts and switch mechanism for a socket of what is commonly known as the "angle type."

In the accompanying drawings,

15 Figure 1 is a side elevation of a socket in which my invention is embodied in one form;

20 Fig. 2 is a side elevation partially in section of the socket at right angles to Fig. 1 and showing the casing parts detached;

25 Fig. 3 is a side elevation of the socket body at right angles to Fig. 2;

Fig. 4 is an enlarged vertical section through portion of the socket showing the 30 switch mechanism;

Fig. 5 is a horizontal section on the line 5—5, Fig. 3;

Fig. 6 is an exploded view showing the 35 elements of the socket body in perspective with some of the conducting parts detached.

Referring to the drawings, the socket as here shown comprises a two-part casing having what may be termed, for convenience, a shell 10 and cap 11 sleeved together and provided within the sleeving area with latching means of any suitable sort such as the elements 12 and 13 of well known type. An attaching nipple 14 is carried by the shell 10 and projects at right angles to the long 40 axis of the socket so that in adjusted position on the fixture pipe the lamp inserted in the socket will stand upright, while the switch-operating chain 15 hangs down through the bell 16 formed centrally of the 45 cap 11 at its lower end.

The socket body within the casing is formed of three insulating buttons 17, 18 and 19. The buttons 18 and 19 have each a flat face and an opposite rounded face so 50 that in assembled position the flat faces may be spaced apart to receive between them a switch mechanism, while the rounded outer faces conform to the cylindrical shape of the socket casing. The button 17 overlies 55 the buttons 18 and 19 at one end and affords

an insulating support for the socket terminals 20 and 21. The standards 22, 23 and 24 serve to space apart the buttons 18 and 19, the two lower standards being insulated from all current-carrying parts of the 60 switch, while the standard 23 overlies on one side of the switch terminals 24 and serves to retain the latter in position on the inner face of button 19. The securing screw 25 for this standard pierces the button 19 and 65 engages on the outer face of the latter an angled strap 26 let into a recess 27 and extending into a seat 28 in the top button 17 where it is engaged by a second securing screw 29 which pierces the latter and over- 70 lies the base of the center contact 21 of the socket thus mechanically and electrically connecting the latter to the button 17 and the plate 26 and simultaneously serving to mechanically secure button 17 with relation 75 to the buttons 18 and 19. On the inner face of the button 19 is formed a ratchet boss 30 having four teeth, one of which is overlaid by the terminal 24, just mentioned, while the diametrically opposite tooth is 80 overlaid by a second switch terminal 32. This establishes electrical connection with one side of the line circuit through the wire terminal 43 beneath which in the recess 49, in the outer face of button 19, the base of 85 the terminal 32 is secured.

On the outer face of the opposite button 18 is arranged a wire terminal strap 33 seated in a recess and secured by a screw 34. The upper end of this strap is angled 90 beneath the button 17, the perforation 35 in the strap registering with a hole 36 in the button through which passes a screw 37 the head of which overlies the yoke 38 engaging the base flange 39 of the screw shell 20. The 95 screw shell is thus continually in the line circuit. A second screw bolt 40 may be provided to more securely hold the screw shell in position on the button 17.

The switch mechanism comprises a rotary switch piece 41 having contact wings 42 which overlie the teeth of the ratchet boss 30 and span the switch terminals 24, 32, in the "on" position of the switch thus completing the line circuit to the socket center 105 contact. The switch contact is rotated by dogs on the oscillating actuating plate 44 which carries the chain rail 45 for the pull chain 15. The return spring 46 is mounted on the switch spindle 47 and engages the 110

tongue 48 on the actuating plate at one end, while its opposite end is engaged in a rectangular adjusting nut 48^a, seated in a rectangular recess in the button 18 and having 5 a slotted outer face which is accessible from the exterior of the switch body for ready adjustment of the tension of the spring.

To facilitate the assembly of the button 17 and the correct positioning thereof with 10 relation to the buttons 18 and 19, a rectangular rib 50 may be formed on the lower face of the button 17. This rib lies between the opposed flat faces of the buttons 18 and 19 in the assembled position of the parts.

15 To prevent the socket as a whole from swiveling in the casing, a boss 51 is formed on one side of the button 17 which engages between a pair of inwardly struck flanges 52 on the shell 10. The spacing bracket 23 20 serves as a stop against which the actuating plate abuts in its position of rest, while the position of this plate is such that the pull chain may freely pass downward and out through the chain bell 16 at the bottom of 25 the cap on the actuation of the switch. The securing nipple 14 through which the wires are led into the switch is so positioned by the notch 53 in the cap 11 that the wires enter at a point between the buttons 18 and 30 19 and the vertical edges of the latter are channeled at 54—55 to accommodate the wires as they pass to the wire terminals 33 and 43 respectively.

The construction of the socket is such that 35 the lamp is held in vertical position while the pull chain, instead of passing out through the side of the casing in the usual manner, passes out at the bottom of the casing and affords a straight downward 40 pull, thus not only putting less strain on the securing nipple but giving a freer and easier action to the mechanism since there is practically no friction between the chain and the bell as it passes through the latter.

45 Various modifications in details of construction will readily occur to those skilled

in the art without departing from what I claim as my invention.

I claim as my invention:—

1. A pull socket having a casing, an insulating body within the casing, said body comprising a top button and lamp terminals carried thereby, and two side buttons connected together and to the top button, said side buttons being spaced apart, a switch 50 mechanism arranged between the side buttons and electrically interposed in the circuit of the lamp terminals, and a pull member for actuating the switch, said pull member extending out through the bottom of the 60 casing, substantially as described.

2. A pull socket having a casing, an insulating body within the casing, lamp terminals carried by said body adapted to hold a lamp on the axis of the casing, a switch 65 spindle mounted on said body and extending transversely to the axis of the casing, a switch device on said spindle, and a pull member for actuating the switch, said pull member passing out of the casing at the 70 lower end of the latter and substantially on the axis thereof.

3. A pull socket having a casing, an insulating body within the same comprising a pair of vertically arranged buttons spaced 75 apart, lamp terminals carried by said body, a wire terminal on each of said buttons, one of said wire terminals being directly connected to one of the lamp terminals, a switch mechanism arranged between the said buttons, and electrically interposed between the other wire terminal and the other lamp terminal, together with a pull member for actuating said switch, said pull member passing out through the bottom of the casing. 85

In testimony whereof I have signed my name to this specification, in the presence of two subscribing witnesses.

GEORGE B. THOMAS.
